UNITED STATES PATENT OFFICE.

CLAUDE W. BUNDE, OF CHICAGO, ILLINOIS, ASSIGNOR TO NATIONAL CANDY COMPANY, OF CHICAGO, ILLINOIS, A CORPORATION OF NEW JERSEY.

DEPOSITING-MACHINE.

1,327,806.

Specification of Letters Patent. Patented Jan. 13, 1920.

Application filed May 17, 1919. Serial No. 297,726.

To all whom it may concern:

Be it known that I, CLAUDE W. BUNDE, a citizen of the United States, residing at Chicago, in the county of Cook and State 5 of Illinois, have invented a certain new and useful Improvement in Depositing-Machines, of which the following is a specification.

My invention relates to depositing machines adapted to operate upon plastic material. While the principle of the invention is applicable to various substances, it is especially adapted to material which is noticeably cohesive; for example, the so-called 10 "dough" used by confectioners for the manufacture of macaroons. Ordinarily confectioners' macaroons are composed of a considerable percentage of shredded cocoanut which renders the material not only plastic, 15 but both cohesive and adhesive. The general object of the invention is to provide a machine for depositing the material in formed pieces of disk or other shape, and to do the work with certainty, uniformity, 20 accuracy and with little attention on the part of the attendant.

Among the specific objects which contribute to this general object are to provide a sliding cut-off valve for forming the 25 pieces; to provide means for venting the cut-off valve; to provide means for keeping the vent of the cut-off valve open; to provide special ejecting means for ejecting the formed pieces from the machine; to provide 30 means for lubricating said ejecting means, and to provide means for timing and correlating the various elements which work together to produce the final result.

I accomplish my objects by the mechanism illustrated in the accompanying drawings, in which—

Figure 1 is a top plan view of the complete machine embodying my invention.

Fig. 2 is a side sectional elevation thereof 45 on the line 2—2, Fig. 1.

Fig. 3 is a cross sectional elevation on the line 3—3, Fig. 2.

Figs. 4 and 5 are detail views showing different pieces of the cut-off valve and 50 ejector.

Fig. 6 is a fragmentary top plan view of the cut-off valve.

Like numerals denote like parts throughout the several views.

In the particular embodiment selected to 55 illustrate the invention, the machine has a base 1 having standards 2, 2 rising therefrom and forming a support for the side frames 3, 3. These parts taken collectively may be regarded as the main frame of the 60 machine. Fastened to the side frames 3 are brackets 4 which support a plate 5 which forms a platform for supporting the upper run of an endless belt 6, as best shown in Figs. 2 and 3. This belt runs over rollers 65 7, 8 mounted upon shafts 9 arranged horizontally at opposite ends of the main frame, as best shown in Figs. 1 and 2. Said belt is designed to have the finished pieces 10, 10 deposited on it in the manner hereinafter 70 described.

Rigidly mounted above the belt is a plate 15 which supports the sliding cut-off valve 16 and has a row of orifices 17 near one end through which the pieces are delivered onto 75 the belt when finished. Said valve has a row of orifices 18 which form dies in which the pieces are formed and transferred from the reservoir to the discharge orifices. Above valve 16 is rigidly mounted a plate 80 20 which has a row of orifices 21 through which the material is forced into orifices 18 when the slide is in the initial position shown in Fig. 2. Mounted upon plate 20 is a reservoir 22 which contains the plastic 85 work material. It is provided with a plunger 23 controlled by racks 24 operated by pinions 25 as best shown in Figs. 1 and 2. Said pinions are rigidly fastened to a shaft 26 and it is desirable, in order to keep the 90 racks and pinions in engagement with each other, to provide yokes 27 which fit loosely over the shaft and back up the racks thus forming guides for the racks and preventing them from becoming disengaged from 95 the pinions. The shaft is given an intermittent rotary motion by means of a ratchet wheel 29 adapted to be engaged by a pawl 30 pivotally mounted upon an arm 31. Said arm fits loosely on shaft 26 and is caused to 100 oscillate by a pitman rod 32 shown among other places at the right side Fig. 3. At the lower end this rod has a fork 33 which straddles the main shaft 35 journaled in the main frame. A roller 37 is mounted on the 105 side of fork 33, said roller running in the track of a shrouded cam 38 rigidly fastened to the end of said shaft 35. By preference

the periphery of the cam 39 is cylindrical and concentric with shaft 35 with the result that by putting a drive belt around the cam the latter performs the additional function 5 of a drive pulley, although it will be understood that any other suitable form of power device may be substituted. The intermittent rotation of the ratchet wheel causes a corresponding lowering of plunger 23 and forces the material to be fed 10 down into the forming and delivering mechanism at the bottom of the reservoir.

The mechanism for reciprocating the slide valve 16 is shown in Figs. 1, 2, and 3. It 15 consists of two arms 42 which are slotted at the upper end to receive the shaft 43 which is fastened to the rear edge of the slide valve by means of brackets 44. At the lower end these arms 42 are rigidly fastened 20 to a rock shaft 46 journaled near the bottom of the machine and oscillated by an arm 47 the upper end of which is pivoted to a fork 48 which straddles shaft 35. Mounted on the side of said fork is a roller 50 which 25 works in the track of a shrouded cam 51 rigidly fastened to shaft 35. Thus the rotation of said cam shaft rotates cam 51 which in turn causes the rock shaft 46 to oscillate and move the arms 42 and slide 30 valve 16 forward and backward in timed relation with the rest of the mechanism.

A link 55 shown in side elevation in Fig. 2 is pivoted at one end to one of the arms 42 and at the other end to an arm 56 which is 35 loosely mounted on shaft 9 and is provided with a pawl 57 adapted to engage the teeth of a ratchet 58. Said ratchet is rigidly fastened to shaft 9 and roller 7 is rigidly fastened to the shaft; consequently when the 40 shaft is rotated it rotates the roller 7 and advances the belt 6.

In addition to the orifice 21, plate 20 has a row of orifices 60 located directly above the delivery orifices 17 in plate 15. These 45 parts are shown in detail in Figs. 4 and 5. The travel of the slide valve 16 is such as to move orifices 18 from a position where they register with the orifices 21 to a position where they register with the orifices 16 50 and 17.

A row of ejectors 62 is rigidly mounted upon a cross-beam 63 the ends of which are supported by links 64. These links are pivoted at their lower ends to arms 65 rigidly 55 fastened to a rock shaft 66 journaled near the lower part of the machine as best shown in Figs. 2 and 3. Said rock shaft is oscillated by means of an arm 67 provided at its upper end with a roller 68 adapted to work 60 in the groove of a shrouded cam 69 rigidly fastened to shaft 35. The parts are so timed that when the slide is moved to delivering position, as shown in Figs. 4 and 5, the ejectors will descend and force the work down 65 onto the belt 6.

According to the best design the ejectors are cupped at their lower extremities so as to form what is virtually a cutting, or at least a scraping edge around the margin, to facilitate a clean removal of the formed pieces 70 and make possible a lubrication of the ejectors where they engage the pieces. A duct 73 is formed in each of the ejectors, its function being to lead the lubricant to the concavity 72 from the supply pipe 74. By 75 preference duct 73 is open at the top and its inner walls are spaced from the outer walls of pipe 74, thus affording a vent. The lubricant ordinarily employed is water which is stored in a reservoir 75 mounted near the 80 upper part of the machine. The flow of lubricant from the reservoir to the ejectors is controlled by a set of valves 76 having levers 77 by which the valves are controlled. The valves are compelled to operate in unison by means of a controlling bar 78 which 85 actuates them. For the sake of simplicity, the connection between the controlling bar and the valve levers is made by simply forming apertures in the bar of a diameter large 90 enough to loosely receive the ends of the levers as shown in detail in Figs. 4 and 5.

The controlling bar 78 is arranged horizontally and is slidingly supported upon stationary brackets 80, 81. It is actuated by a timing mechanism which may assume various forms, but is suitably illustrated in the drawings, especially Figs. 1, 2, and 3. In this form a dog 82 is pivoted to bar 78 and is backed up by a spring 83 which urges it 100 toward the end 85 of a bell crank which is pivoted upon a pin 86 carried by bracket 81. The other arm 87 of said bell crank is pivotally connected to a connecting rod or pitman 88 which, at the opposite end, is articulately connected by means of a ball and socket joint 89 to the upper end of the arm 42 previously mentioned. It will be evident that, as arm 42 oscillates back and forth, it will produce a corresponding oscillatory 110 movement of the arm 85. The arrangement is such that when arm 85 has swung to a point near one end of its travel it will be engaged by the dog 82. The return movement of the arm will cause the dog to move 115 with it and move the controlling bar 78 in opposition to the force of the helical compression spring 90 which is interposed between bracket 80 and shoulders 91 formed on the controlling bar as shown near the 120 bottom of Fig. 1. After the arm 85 has thus moved the dog and bar sufficiently to open the valves 76 for a moment, the cam shaped nose of the dog will engage a stationary pin 93 mounted upon the bracket 81 and force 125 the dog out of engagement with arm 85. As soon as the dog is thus released, the spring 90 will quickly return the controlling bar to the normal position shown in Fig. 1, shutting off the valves and putting the dog 130

in position to repeat the operation. This mechanism may be characterized as including a spring actuated detent which is automatically releasable for enabling the valves 5 to be quickly returned to closed position.

Drain ducts 95, shown in detail in Figs. 4 and 5, are formed in the bottom of plate 20 for leading any excess of lubricating water away from the ejecting mechanism. 10 This permits the surplus to run off on to the top of slide valve 16 and thence down into the tray 96 secured to plate 15.

From each of the orifices 18 in slide valve 16 there leads a channel 98 formed in the 15 bottom of the valve and extending toward orifice 17. These ducts form vents for the escape of air when the plastic work material is being forced down into orifice 18. Pins 99 having pointed tops are mounted in plate 20 15 is position to work in the channels 98 to keep them clean. As the valve slides back and forth the pins scrape the sides of the channels and remove any material which may be adhering thereto.

25 The operation of the mechanism will now be readily understood: In starting, the reservoir 22 is filled with the work material and the plunger 23 is lowered by hand until it contacts it. In initial position the water 30 valves 76 are closed and the slide valve 16 is in such position that its mold orifices 18 will register with the die orifices 21 in the plate 20. When the machine is started, the plunger 23 will commence gradually to descend 35 and fill the mold orifices. When they are completely filled, arm 42 moves toward the right, Figs. 2, 4, and 5, thus moving the mold plate or valve 16 toward the right and causing the mold orifices 18 to move from 40 charging position shown in Fig. 1 to discharging position shown in Fig. 4. At the same time the right edge of the die openings 21 severs the material in the mold orifices from the material remaining in the die orifices. 45 At the same time also, the blank surface of the slide valve or mold plate 16 closes the bottom of the die orifices. While the part 16 is traveling from charging to discharging position, the ejectors remain ele- 50 vated, but about this time the water valves 76 are momentarily opened. The lower rims of the ejectors are so near the top surface of part 16 that the latter practically forms a closure for the ejectors and consequently the 55 water rises high enough to wet their inner surfaces for a short distance up from the bottom. The amount of water need not be very great, but in any event it comes between the work pieces and the ejector and 60 prevents the former from sticking to the latter. The mold orifices 18 finally reach the discharging position, Fig. 4, where they are uncovered both top and bottom. When the orifices 18 arrive at the orifices 17 and 65 60 the slide valve remains stationary and the

ejectors commence to descend. The descending ejectors force the work pieces down through the orifices 18 and 17 and cause them to drop upon the endless delivery belt 6. In descending, the ejectors crown the 70 tops of the work pieces—i. e., they round them so that they present a convex surface when viewed from above. The precise shape of the finished and delivered article may, of course, be varied by varying the shape of 75 the ejector and parts coöperating therewith. After the ejectors have descended far enough to eject the finished pieces from plate 15 they rise again to initial position whereupon the slide valve 16 commences its 80 return travel and finally arrives at initial position. The cycle is then repeated.

When the work material is being forced down into the orifice 18 in the slide valve the air which would otherwise be confined, 85 escapes through the channels 98 to the open orifices 17. Thus there is nothing to prevent the mold orifices 18 from being completely filled and the material compacted.

In case more water than is necessary is 90 released from reservoir 75 by the valves 76, no harm is done, for the surplus may readily run off through the vent ducts 95. In fact, no harm is done if the ejectors are practically flooded, for the water remains in contact with the goods for only a short space of time and cannot do any harm.

It is desirable that the discharge orifice in the bottom plate be of the same size as the mold orifice in the slide valve, as shown. 100 The advantage is that with this construction, when the ejector descends, it forces the work piece down through the discharge orifice, and the friction between the work piece and the walls of the discharge orifice not 105 only smooths the sides of the work piece, but tends to round off its lower corners slightly, thus avoiding any possibility of rough cut corners and giving the work piece a more finished appearance.

110 It will be understood that various details of construction may be suitably altered without departing from the spirit of the invention.

Having thus described my invention what 115 I claim as new and desire to secure by Letters Patent, is:—

1. A depositing machine having a reservoir for containing the work material, the reservoir having a die opening at the bottom, a bottom plate beneath said die opening, and a valve slidingly mounted between the bottom plate and the die opening and having a mold orifice, said mold orifice being beneath the die opening when the valve is in 120 charging position, and the bottom of the mold orifice being covered at this time by the bottom plate, and the mold orifice being uncovered by the bottom plate when the valve is in discharging position, the valve 125 130

having a duct leading from the bottom of the mold orifice to the atmosphere for venting the mold during the act of charging.

2. A depositing machine having a mold 5 adapted to occupy a charging and a discharging position, the mold orifice being open top and bottom when the mold is in discharging position, and an ejector adapted to enter the mold orifice for removing the 10 formed piece from it when the mold is in discharging position, said ejector having a concavity at the bottom for crowning the piece as it is forced from the mold orifice.

3. A depositing machine having a mold 15 adapted to occupy a charging and a discharging position, the mold orifice being open top and bottom when the mold is in discharging position, and an ejector adapted to enter the mold orifice for removing the 20 formed piece from it when the mold is in discharging position, said ejector having a concavity at the bottom for crowning the piece as it is forced from the mold orifice, and said ejector having an opening leading 25 from a point near the top of the concavity for venting purposes.

4. A depositing machine having a mold provided with an orifice open top and bottom, an ejector adapted to descend into the 30 filled mold for discharging the work piece therefrom, and a duct leading down through the ejector and adapted to supply a lubricating fluid to the acting surface of the ejector approximately concentrically therewith.

35 5. A depositing machine having a mold adapted to occupy a charging and a discharging position, the mold orifice being open top and bottom when the mold is in discharging position, an ejector adapted to 40 enter the mold orifice for removing the formed piece therefrom, said ejector having a duct leading down through it and terminating at the bottom where the ejector contacts the formed piece, and means for controllably supplying a lubricant to said duct.

45 6. A depositing machine having a reservoir, a mold adapted to slide from charging position beneath said reservoir to a discharging position at one side thereof, said 50 mold having an orifice which is open top and bottom when the mold is in discharging position, an ejector adapted to descend into the mold orifice when the mold is in discharging position, a duct leading down 55 through the ejector to supply a lubricating fluid to the acting surface thereof, a valve for controlling the flow of lubricating fluid in said duct, and mechanism common to said mold and valve for actuating them in timed 60 relation.

65 7. A depositing machine having a mold adapted to occupy a charging and a discharging position, the mold orifice being uncovered top and bottom when the mold is in discharging position, means for supplying

a lubricant to the top of the material within the mold when the latter is in discharging position, an ejector, a guide having an orifice for guiding the ejector to the mold orifice when the latter is in discharging position, said guide having a drainage duct leading from the side of the guide orifice. 70

8. A depositing machine having a reservoir for containing the work material, said reservoir having a die opening at the bottom, a bottom plate beneath the die opening, a valve slidably mounted between the bottom plate and die opening and having a mold orifice, said mold orifice being beneath the die opening when the valve is in charging position, and the bottom of the mold orifice being covered at this time by the bottom plate, and the mold orifice being uncovered by the bottom plate when the valve is in discharging position, the valve having a channel leading from the side of the mold orifice to the atmosphere for venting the mold orifice, and means for scraping said channel as the valve travels. 80

9. A depositing machine having a reservoir for containing the work material, said reservoir having a die opening at the bottom, a bottom plate beneath the die opening, a valve slidably mounted between the bottom plate and die opening and having a mold orifice, said mold orifice being beneath the die opening when the valve is in charging position, and the bottom of the mold orifice being covered at this time by the bottom plate, and the mold orifice being uncovered by the bottom plate when the valve is in discharging position, the valve having a channel in the bottom leading from the side of the mold orifice to the atmosphere for venting purposes, and an upstanding stationary 100 pin adapted to scrape the channel free from surplus material during the travel of the valve. 105

10. A depositing machine having a mold plate slidable from a charging to a discharging position and return, said plate having a mold orifice extending through it, a bottom plate for closing the bottom of the mold orifice when the mold plate is in charging position, the mold orifice being uncovered when 115 the mold plate is in discharging position, means for charging the mold orifice, and a plunger for ejecting the formed piece from the mold orifice when the mold plate is in discharging position, said plunger having a 120 concave acting surface and a thinned rim adapted to scrape the sides of the mold orifice, and simultaneously configurate the top of the piece. 115

11. A depositing machine having a mold plate slidable from a charging to a discharging position and return, said plate having a mold orifice extending through it, a bottom plate for closing the bottom of the mold orifice when the mold plate is in charging po- 130

5 sition, the mold orifice being uncovered when the mold plate is in discharging position, means for charging the mold orifice, a plunger for ejecting the formed piece from the mold orifice when the mold plate is in discharging position, said plunger having a thined rim adapted to scrape the sides of the mold orifice, and simultaneously configurate the top of the piece, and means for intermittently supplying a lubricant to the acting surface of the plunger.

10 12. A depositing machine having a mold plate, slidale from a charging to a discharging position and return, said plate having a mold orifice extending through it, means for covering the bottom of the mold orifice when the mold plate is in charging position, and for uncovering it when the mold plate is in discharging position, means 15 for charging the mold orifice, a plunger for ejecting the formed piece from the mold orifice when the mold plate is in discharging position, a duct leading to the acting surface of the plunger for conveying lubricant thereto, a valve for controlling the flow of lubricant in said duct, and correlating means for moving the mold plate and the valve in timed relation.

20 25 13. A depositing machine having a mold plate adapted to occupy a charging and a

discharging position, said plate having a mold cavity, means for charging the same, an ejector having a concave bottom for ejecting the finished piece from the mold cavity when the plate is in discharging position, 35 the mold plate forming a closure for the bottom of the ejector before the plate reaches discharging position, and means for supplying water to the concave bottom of the ejector while the same is closed by the mold 40 plate.

14. A depositing machine having a mold plate provided with a mold cavity, and capable of occupying a charging and a discharging position, means for charging the 45 mold plate, an ejector for ejecting the formed piece from the mold cavity when the latter is in discharging position, and means for lubricating the acting surface of the ejector, said means including a controlling 50 valve, a controlling bar for actuating the valve, a detent for moving said bar in one direction, an arm for actuating said detent, means for causing the disengagement of the arm and detent when the bar has traveled the 55 proper distance, and means for returning said bar to normal position.

In witness whereof, I have hereunto subscribed my name.

CLAUDE W. BUNDE.
